UNITED STATES PATENT OFFICE.

RICHARD HOW, OF MEDARYVILLE, INDIANA.

RAILWAY-TIE.

No. 926,418.

Specification of Letters Patent.

Patented June 29, 1909.

Application filed December 14, 1908. Serial No. 467,403.

To all whom it may concern:

Be it known that I, RICHARD HOW, a citizen of the United States, residing at Medaryville, in the county of Pulaski and State of Indiana, have invented certain new and useful Improvements in Railway-Ties; and I do declare the following to be a full, clear, and exact description of the invention, such as will enable others skilled in the art to 10 which it appertains to make and use the same.

My invention relates to railway ties, and particularly to that type which are constructed of cement or other compositions.

15 The object of the invention is to provide a device of this character which may be conveniently transported and which will be cheap to manufacture and easy to apply in practice.

20 A further object of the invention is the provision of novel means for supporting the rail upon the tie.

With these and other objects in view, the invention consists of certain novel features 25 of construction, combination and arrangement of parts, as will be more fully described and particularly pointed out in the appended claims.

In the accompanying drawings, Figure 1 30 is a side elevation of the tie showing the rails in section thereon; Fig. 2 is a top plan view; Fig. 3 is a fragmentary longitudinal section on line 3—3 of Fig. 2; Fig. 4 is a transverse section on the line 4—4 of Fig. 2, and Fig. 5 35 is a horizontal section on line 5—5 of Fig. 1.

Referring more especially to the drawings, 1 and 2 represent the two halves of a tie. These halves are both alike and are provided at their inner ends with bushed apertures 3 40 through which the clamping bolts 4 are adapted to pass so as to secure the members together by means of the clamping plates 5. Each tie is preferably pyramid-shaped in cross section and has embedded in its surface 45 a plurality of reinforcing L-irons 6.

At each end of the tie *i. e.*, at the outside end of each member, I provide a rubber or other flexible cushion 7 and mount thereupon the wooden block 8. The cushion 7 and the

block 8 are both preferably made with a half 50 notch 9 on the outside of each piece so as to receive the locking rib 10 which is made integral with the inner side of the clips 11. These clips overlap the rail 12 and are secured to the tie by means of bolts 13 which 55 pass through the clips and through bushed openings 14 in the tie.

By the above construction of cushion blocks I am enabled to replace them at any time without raising the tie to remove the 60 bolts, or without any considerable trouble, as is the case in some instances. A slight pressure under the center will raise the blocks free of the ribs so that they may be easily removed. When in place, the bolts 65 effectually prevent any sliding or slipping of the parts and the rail is always insured a firm and resilient base or support.

From the foregoing description, taken in connection with the accompanying drawings, 70 the construction and operation of the invention will be readily understood without requiring a more extended explanation.

Various changes in the form, proportion 75 and the minor details of construction may be resorted to without departing from the principle or sacrificing any of the advantages of this invention as defined in the appended claims.

Having thus described my invention, what 80 I claim and desire to secure by Letters-Patent is:

1. In a device of the class described, a body, a pair of cushioning members seated on said body, said cushioning members being 85 of different resiliency and having a notch on each side thereof, rail securing means adapted to hold a rail upon said cushioning members, and means formed on said rail securing means adapted to engage the notches of said 90 members to prevent their displacement.

2. In a device of the class described, a body, a cushioning member seated on said body, and having notches in its sides, a second cushioning member mounted upon the 95 first member and having notches registering with the notches in the first cushioning member, said second cushioning member having

less resiliency than the first mentioned cushioning member, rail securing means adapted to hold a rail upon said cushioning members, and lugs on said securing means for engaging 5 the notches of said cushioning members to hold them from displacement.

In testimony whereof I have hereunto set

my hand in presence of two subscribing witnesses.

RICHARD HOW.
